UNITED STATES PATENT OFFICE.

GEORGE S. CALDWELL, OF AUBURN, NEW YORK.

DESIGN FOR A GUARD-RAIL FOR WAGONS, SLEIGHS, &c.

SPECIFICATION forming part of Design No. 19,893, dated June 10, 1890.

Application filed April 9, 1890. Serial No. 347,275. Term of patent 7 years.

To all whom it may concern:

Be it known that I, GEORGE S. CALDWELL, of Anburn, Cayuga county, New York, have invented and produced a new and original Design for Guard-Rails for Wagon or Sleigh Dashes, of which the following is a specification, reference being had to the accompanying drawing, forming part hereof, the said drawing showing an elevation of my design.

My design shows an elongated flat plate or bar A, on the surface of which appear numerous regularly-disposed countersinks B, and through the center of each countersink appears an aperture C. At the extremities of the bar A appear rods D, which may be

scroll-shaped, as shown, and terminate in an ornamental figure, as E.

My design relates to wagon or sleigh dashes, and more particularly to a bar or plate on the upper edge of the dash-board and serving as 20 a guard.

I claim—

The design for a guard-rail for wagon or sleigh dashes, substantially as herein shown and described.

GEORGE S. CALDWELL.
